W. M. HEDRICK AND E. G. ERVIN,
EXHIBITING DEVICE FOR CERTIFICATES, PICTURES, AND THE LIKE,
APPLICATION FILED FEB. 11, 1919.

1,323,982.

Patented Dec. 2, 1919.

FIG. IV

William M. Hedrick
Edwin G. Ervin. Inventors

FIG. V.

By Mason Tomnick & Lawrence,
Attorneys

UNITED STATES PATENT OFFICE.

WILLIAM M. HEDRICK AND EDWIN G. ERVIN, OF FORT LOGAN, COLORADO.

EXHIBITING DEVICE FOR CERTIFICATES, PICTURES, AND THE LIKE.

1,323,982.

Specification of Letters Patent.

Patented Dec. 2, 1919.

Application filed February 11, 1919. Serial No. 276,447.

To all whom it may concern:

Be it known that we, WILLIAM M. HEDRICK and EDWIN G. ERVIN, citizens of the United States, residing at Fort Logan, in the county of Arapahoe and State of Colorado, have invented certain new and useful Improvements in Exhibiting Device for Certificates, Pictures, and the like; and we do hereby declare the following to be a full, clear, and exact description of the invention, such as will enable others skilled in the art to which it appertains to make and use the same.

Our invention relates to improvements in exhibiting or framing device for certificates, pictures and the like which has two sides or faces to be exhibited.

An object of our invention is to provide a device or frame, of the class described, having suitable means for attaching the same to a wall and with means for exhibiting both sides of the contained certificate, picture or the like, and for causing the frame carrying the certificate or picture to normally lie in a plane substantially parallel to the wall.

A further object of our invention is to provide a device of the character described which shall be simple, substantial and inexpensive, and having provision to facilitate the insertion and removal of the contained certificate or picture.

With these and other objects in view our invention comprises certain novel construction, combination and arrangement of parts as will be hereinafter more fully described and claimed, and as illustrated in the accompanying drawing, in which like characters of reference indicate corresponding parts throughout the several views and in which

Figure 1 is a side elevation of our improved exhibiting device, showing the picture carrying frame in position perpendicular to the wall on which the device is mounted.

Fig. 2 is a front edge elevation of the device in the same position as in Fig. 1.

Fig. 3 is a fragmentary sectional view on line 3—3 of Fig. 1.

Fig. 4 is a view of a fragment of Fig. 1 on an enlarged scale.

Fig. 5 is a plan of the fragment shown in Fig. 4, as seen from below.

The construction will be best understood

from a description of the device as now constructed and used, it being understood that many of the details of construction can be varied and likewise variation may be made in the use, without in either case, departing from the principle of the invention. 55

The particular use for which our invention was made is the framing and exhibiting of certificates of honorable discharge from the army and navy, which certificates bear upon the reverse side the enlistment 60 record of the discharged soldier or sailor. It is, therefore, desirable that the certificate be framed and supported in such manner that both sides may be easily exhibited. 65 It is also desirable that the frame-work be so constructed that the certificate may be easily inserted and removed.

To accomplish these purposes we provide a mounting strip 1, which may be secured to a wall indicated at 2, by any suitable 70 means such as screws for which the holes 3 may be provided in the strip 1.

In the strip 1, we insert suitable means such as screw-eyes 4 and 5 for the mounting of the frame, which we will now describe. 80

The frame is constructed in two parts indicated at 6 and 7, respectively. Both portions of the frame consist of channelled sheet metal. Portion 6 consists of a channelled member of three sides, the top and bottom 85 portions of which correspond in length with the width of the picture or certificate to be framed, the upright portion of member 6 corresponding to the height of the picture or certificate to be framed. The width of 90 the channel in member 6, and likewise in member 7, is sufficient to accommodate the picture or certificate, and preferably to likewise accommodate two plates of glass, one to be placed over each face of the certificate 95 or picture. Fig. 3 clearly illustrates the two plates of glass positioned within the channel.

The ends of the top and bottom portions of member 6 are drawn out, flattened and bent upon themselves, forming ears or lugs 100 8 for the mounting of the frame. This portion is bent upon itself as clearly seen in Fig. 4, the purpose being to strengthen the ear or lug.

The fourth side of the frame consists of 105 member 7 which is likewise a channel member with the channel corresponding to that of member 6, and in length this member is

equal to the height of the picture or certificate to be framed. The ends of member 7 are likewise drawn out and flattened into ears or lugs 9 for the purpose of mounting.

5 The ears or lugs 8 and 9 are provided with holes at their centers for the reception of the mounting wire or rod 10 hereafter described.

When the parts are prepared we insert in the member 6 the picture or certificate to be 10 mounted preferably with a plate of glass on each side thereof. Three edges of the picture or certificate and the inclosing glass are thus framed. The remaining edge is then covered by member 7. This brings the 15 ears or lugs 8 and 9 into alinement and the holes therethrough are thus caused to register. The frame-work is then inserted between the screw-eyes 4 and 5 so that the holes in the ears or lugs 8 and 9 register with the 20 holes or eyes of the screw-eyes. The wire or mounting rod 10 is then inserted through the eyes and through the holes in the ears or lugs 8 and 9, and in this manner the rod 10 serves the double purpose of binding the 25 frame together and providing a pivotal support therefor. The mounted certificate or picture may then be turned to either side upon the rod 10 so that either side of the picture or certificate may be exhibited as 30 desired.

In order that the frame shall not stand out away from the wall but, in whatever position it may be left, shall automatically swing back and lie against the wall, we so 35 construct the device as clearly shown in Fig. 1, that the screw-eye or mounting 5 shall extend farther from the wall than the screw-eye or other mounting 4, and that the bottom of the frame shall be held farther from the 40 wall than the top thereof. By mounting the frame in this position it will, of its own weight turn or fall from the perpendicular position shown in Fig. 1 and will come to rest in contact with the wall upon which it is 45 mounted and will thus at all times remain in a plane substantially parallel with such wall. On this account either one side or the other of the certificate or picture will always appear as a framed certificate or picture hanging 50 against the wall.

The rod or wire 10 is provided with a bent portion 11 or other suitable means for holding it against dropping out of place.

What we claim is:

55 1. In an exhibiting device for certificates,

and the like, a framing member for engaging a plurality but not all of the edges of the certificate, lugs on the ends thereof, a second member for framing the remaining edge or edges of the certificate, lugs on the 60 ends of said second member, and means attached to a wall for swingingly supporting said frame by means of said lugs.

2. In an exhibiting device for certificates, and the like, a framing member for engaging a plurality but not all of the edges of the certificate, lugs on the ends thereof, a second member for framing the remaining edge or edges of the certificate, lugs on the 65 ends of said second member, means attached to a wall for swingingly supporting said frame by means of said lugs, and in position wherein the lower portion of the frame shall be supported farther out from the wall than the upper portion thereof.

3. In an exhibiting device for certificates and the like, a framing member comprising a channel member engaging a plurality but not all of the edges and a portion of the adjacent sides of the certificate and having its 80 ends flattened to form lugs, a complementary framing member comprising a similar channel member adapted to engage the remaining edge or edges and a portion of the side walls of the certificate and having its 85 ends flattened to form lugs adapted to aline with the lugs on said first named channel member and identical means for engaging said lugs to bind the framing members together and form a pivotal support therefor.

4. In an exhibiting device for certificates and the like, a framing member, comprising a channel member engaging a plurality but not all of the edges and a portion of the adjacent sides of the certificate, and having its 90 ends flattened to form lugs, a complementary forming member comprising a similar channel member adapted to engage the remaining edge or edges and a portion of the side walls of the certificate and having its ends 95 flattened to form lugs adapted to aline with the lugs on said first named channel member, alining openings in said lugs and a pin inserted through said openings to bind the frame together and form a pivotal support 100 therefor.

In testimony whereof we affix our signatures.

WILLIAM M. HEDRICK,
EDWIN G. ERVIN.
